(57) **CLAIM**

The ornamental design for a flexible medical container, as shown and described.

DESCRIPTION

FIG. 1 is a front perspective view of a flexible medical container, showing our new design;

FIG. 2 is a front view thereof;

FIG. 3 is back view thereof;

FIG. 4 is side view thereof;

FIG. 5 is a top view thereof; and,

FIG. 6 is a bottom view thereof.

The broken lines show portions of the flexible medical container that form no part of the claimed design.

1 Claim, 5 Drawing Sheets
